(57) **CLAIM**

The ornamental design for an enclosure as shown and described.

DESCRIPTION

FIG. 1 is a perspective view of one embodiment of an enclosure;

FIG. 2 is a right side view of the enclosure of FIG. 1;

FIG. 3 is a left side view of the enclosure of FIG. 1;

FIG. 4 is a top view of the enclosure of FIG. 1;

FIG. 5 is a bottom view of the enclosure of FIG. 1;

FIG. 6 is a front view of the enclosure of FIG. 1; and

FIG. 7 is a rear view of the enclosure of FIG. 1.

Broken lines show portions of the enclosure that form no part of the claimed design.

1 Claim, 6 Drawing Sheets
